(57) **CLAIM**

I claim the ornamental design for an eyewear strap cover, as shown and described.

DESCRIPTION

FIG. 1 is a top rear perspective view of an eyewear strap cover. FIG. 2 is a top view of the eyewear strap cover shown in FIG. 1.

FIG. 3 is a front view of the eyewear strap cover shown in FIG. 1.

FIG. 4 is a rear view of the eyewear strap cover shown in FIG. 1.

FIG. 5 is a bottom view of the eyewear strap cover shown in FIG. 1.

FIG. 6 is a right side view of the eyewear strap cover shown in FIG. 1; and,

FIG. 7 is a left side view of the eyewear strap cover shown in FIG. 1.

The portions of the eyewear strap cover and environment shown in broken lines are for illustrative purposes only and form no part of the claimed design.
